UNITED STATES PATENT OFFICE

WILLIAM P. STUNZ, OF LANSDOWNE, MARYLAND, ASSIGNOR TO SAFE DEPOSIT AND TRUST COMPANY OF BALTIMORE, A CORPORATION OF MARYLAND

TELEPHONIC INSTRUMENT

Application filed May 9, 1928. Serial No. 276,361.

My invention relates to loud speaking sound transmitting instruments and has for its particular object to provide greater amplitude, and improved quality in tone, volume and distinctness of sound waves carried to a receiver from a transmitter or other source.

Also to provide a mechanism which will automatically compensate for any difference 10 or change of amplitude.

Also further to provide an extremely sensitive loud speaking instrument in which the diaphragm is maintained in its normal floating or balanced position through the medium 15 of its cushion gaskets, rocking lever armatures and energy of its permanent horseshoe magnets.

In receivers of this general type heretofore made which embody a diaphragm, a 20 permanent magnet, an electro-magnet, and an arm or lever of the armature operating upon the diaphragm, with an air space between the armature and core of the electro-magnet, and wherein the resiliency of the 25 diaphragm and its elastic or cushioned seat tended to balance the diaphragm against the pull of the permanent magnet very good results were obtainable up to a given amplitude but when a greater amplitude was desirable 30 difficulties were encountered in that the two forces, that is, the resiliency of the diaphragm and the pull of the permanent magnet failed to react or compress with the same pressure ratio and consequently the instrument failed 35 to give fully satisfactory results under a greater amplitude of movement. The difficulties are overcome under the present invention, wherein in the magnetic pull of the permanent magnet on the diaphragm held between the rubber rings or gaskets is balanced so that the 40 diaphragm is responsive in both directions of movement under practically the same pressure ratio, thereby obtaining greater amplitude of movement with greater volume and strength of sound waves and better quality 45 in tone and clearness of delivery.

To accomplish the foregoing, the invention comprises certain new and novel improvements hereinafter particularly described and clearly defined by the appended claims; ref-

erence being had to the accompanying drawings forming a part hereof, and in which,

Figure 1 is a plan view showing one form of an instrument embodying the invention, the housing being shown in section;

Figure 2 is a sectional view taken on line 55 2-2 of Fig. 1, looking in direction of the arrows.

Figure 3 is a sectional view taken on line 3-3 of Fig. 2, looking in the direction of the 60 arrows, and

Figure 4 is an end elevation of the device.

In the drawings, the numeral 1 designates a housing in which may be secured a base member 2 having a central opening 2a provided with flange 2b which with a plate 5 is adapted to form an annular recess 2c wherein the diaphragm 3, having a rubber cushioning ring 4 on each side thereof, is clamped, (see Fig. 3). The proper resiliency of the cushioning effect upon the diaphragm 3 may be had by adjusting the nuts 7 upon the supporting posts 6, 6a and 6b. The plate 5 has an extending tube 5a adapted to receive a sound distributor, or loud speaker horn (not shown).

The supporting post 6 extends some distance from the base member 2 and has secured thereto a bracket member 8, having oppositely disposed arms 9 to which are securely fixed the permanent horseshoe magnets 10 and 11. One arm of each permanent magnet is slightly longer than its mate, and to the ends of said long arms are fastened by screws 10a and 11a, the pole plates 10b and 11b, provided with reduced portions to form cores 10c and 11c, upon which are mounted the induction coils 10d and 11d, and forming two electro-magnets.

The pole pieces or cores 10c and 11c of the induction coils are shown as terminating at a point below the plane surfaces 10e and 11e of the short arms 10f and 11f of the magnets 10 and 11 to provide air gaps 17 and 17a between the cores and armatures of the cores, as illustrated; but the air gaps may be otherwise formed, for instance, the armatures may be set at an inclination to a vertical plane passing through the plane surfaces 10e and 11e of the short arms 10f and 11f of the per-

manent magnets whereby the inner or rear edges of the armatures contacting with the short arms will constitute a knife-edge bearing on the short arms, and which is an obvious change to the skilled in the art to form the air gaps.

The inner edge of the flat surface of each armature 12 and 13 overlaps the permanent magnets 10 and 11, respectively, sufficiently to form a proper fulcrum thereon, as at 12b and 13b, upon the outer edges of the short arms 10f and 11f of the permanent magnets, and are magnetically held to the surfaces 10e and 11e of the permanent magnets 10 and 11, as shown (Figs. 2 and 4). The armatures 12 and 13, have inwardly extending levers 12a and 13a, respectively, whose ends terminate at a point approximately over the center of the diaphragm 3.

The diaphragm 3 has secured thereto, centrally, and extending at right angles therefrom, a stem or plunger rod 14, preferably a thin flat strip of aluminum or other suitable material (see Figs. 3 and 4). This stem 14 is provided with slots 15 and 16 which are properly spaced from each other; said slots 15 and 16 being adapted to receive and engage the inner notched ends of the armature levers 12a and 13a. It will be seen when the levers 12a and 13a are pulled towards each other and their ends engaged in the slots 15 and 16, that positive air spaces as at 17 and 17a are formed between the under or inner surface of the armatures 12 and 13, and the ends of the cores 10c and 11c of the electro-magnets. In making assemblage of the parts, by manipulating the supporting posts 6, 6a and 6b, the permanent magnets may be moved slightly to or from the base member 2 until the air gaps or spaces 17 and 17a are equal; the nuts on the said posts are then set, a magnetic balance of the armature levers and cushioned diaphragm having been thereby established. If at any time, after the parts have been assembled, it is desired to change or vary the air space between the two armatures and the pole-pieces of the electro-magnets, it can be effected by adjustment on post 6. Provision for this is made by making the underface of the lateral arms 9 of member 8 convex as shown in an exaggerated degree at 9a in Figs. 1 and 2 of the drawing. This convexity admits of a sufficient degree of rocking or flexibility at the union or joint between the arms 9 of the member 8 and the two permanent magnets which are attached by the bolts shown to the extended arms of member 8.

If it be desired to change the air gap between only one of the armatures and its companion pole-piece, the adjustment is effected on post 6a or 6b, as the case may be, so that an individual adjustment of the air gap of the particular unit desired is obtained without changing the air gap of the

other individual unit, the convex face of the arm to which is attached the permanent magnet of the individual unit in which adjustment is being made providing for the strain on the joint or union of that particularly magnet without affecting the magnet of the other unit in which adjustment is not desired. It will thus be observed that provision is made for simultaneous adjustment of the air gaps of both armatures, and also for adjustment of the air gap of one individual unit independent of the other unit.

The balancing of the movable parts leaves the diaphragm free to handle the vibrations set up by the fluctuation of the sound wave currents passing through the induction coils 10d and 11d, thus providing a sensitive mechanism which will operate smoothly, quietly, and automatically adapt itself to volumes of various degrees of strength, and greater variations in amplitude. The electro-magnets 10d and 11d (see Figs. 1 and 2), are similarly wound and connected to the source of electric energy, either in series or parallel, but with one connected in the opposite polarity to the other, that is, in one electro-magnet the current enters by the inside wire and passes out by the outside wire, and in the other enters by the outside wire and leaves by the inside wire, whereby the two units act in unison and in the same direction on the diaphragm. For illustration, the vibrating current entering the magnet 10d by the inside wire 10h, passes out by the outside wire 10i, while the current which enters the electro-magnet 11d by the outside wire 11h, passes out by the inside wire 11i; this arrangement increases the pull of one unit while decreasing the pull of the other.

The shorter arm of each permanent magnet is shown as having its end on an oblique angle, or diagonally. This permits the armatures 12 and 13 to be set or mounted diagonally on the pole piece of the permanent magnet so as to be practically fulcrumed along the diagonal edge of the pole of the magnet to conform to the diagonal positioning of the arms or levers which converge towards the rod or stem which connects them to the center of the diaphragm 3, and thus the armatures have a substantially uniform lap and even fulcrum on the pole pieces of the permanent magnets, as illustrated in Fig. 2 of the drawing.

I have illustrated and described my invention in the preferred form, and have given the preferred details of construction, but changes may be made therein and be within the scope of the invention.

Having described my invention, and set forth its merits, what I claim is:—

1. In a telephonic instrument, a vibratable diaphragm from which wave producing vibrations are transmitted, a plurality of armatures each fulcrumed on a permanent mag-

net, lever-arms extending from said armatures and having their free ends connected with the vibratable diaphragm to exert a pull in opposite directions thereon for balancing the diaphragm, and electro-magnets having their cores spaced by an air gap from the magnetically fulcrumed armatures, the windings of one electro-magnet being connected in opposite polarity to the other for action in unison and in the same direction on the diaphragm.

2. In a telephonic instrument, a vibratable diaphragm from which wave producing vibrations are transmitted, a plurality of permanent magnets, an armature fulcrumed on one pole of each magnet and provided with a laterally extending lever, means connecting the free ends of both levers with the diaphragm, the armature and lever of one magnet lying in a different plane from the other to cause the levers to exert a pull in opposite directions for balancing the diaphragm.

3. In a telephonic instrument, a vibratable diaphragm from which wave producing vibrations are transmitted, a plurality of permanent magnets, each having one arm shorter than the other and positioned with the short arm of one opposite the long arm of the other, and the ends of the short arms defining an oblique line, electro-magnets supported from the long arms of the permanent magnets, armatures fulcrumed on the short arms of the permanent magnets along the oblique line thereof, and provided with levers extending towards the central line of the diaphragm, the armatures being spaced from the cores of the electro-magnets, and means connecting the free ends of the levers with the central portion of the diaphragm, the diaphragm being balanced in its vibrations by counter-pressure transmitted through the levers of the armatures actuated by the electro-magnets.

In testimony whereof I affix my signature.

WILLIAM P. STUNZ.

CERTIFICATE OF CORRECTION.

Patent No. 1,812,571.

Granted June 30, 1931, to

WILLIAM P. STUNZ.

It is hereby certified that the above numbered patent was erroneously issued to "Safe Deposit and Trust Company of Baltimore, a Corporation of Maryland", as assignee, whereas said patent should have been issued to Safe Deposit and Trust Company of Baltimore, a Corporation of Maryland, as trustee under the will of George R. Webb, as shown by the records of assignments in this office; and that the said Letters Patent should be read with this correction therein that the same may conform to the record of the case in the Patent Office.

Signed and sealed this 11th day of August, A. D. 1931.
